UNITED STATES PATENT OFFICE.

CHARLES C. GEBHARDT, OF RICHMOND, VIRGINIA.

BOX-FASTENER.

1,177,615.

Specification of Letters Patent.

Patented Apr. 4, 1916.

Application filed September 8, 1915. Serial No. 49,571.

To all whom it may concern:

Be it known that I, CHARLES C. GEBHARDT, a citizen of the United States, residing at Richmond, in the county of Henrico and State of Virginia, have invented new and useful Improvements in Box-Fasteners, of which the following is a specification.

This invention relates to package clips especially designed for use in connection with 10 corrugated cardboard shipping boxes or the like, and which when in applied position upon the box not only effectively holds the sealing flaps thereon closed, but materially increases the rigidity of the walls of the 15 box, affording considerable increased protection of the contents thereof.

Specifically stated the primary object of the invention resides in the provision of a clip including a pair of branch portions 20 struck to provide attaching spurs, the branches being disposed substantially at an obtuse angle with relation to each other and adapted to be singly forced into engagement with its respective wall of the package, the 25 prongs on one branch being disposed at right angles to the prongs on the other branch to prevent splitting or cutting of the walls of the package which would obviously result in the casual separation of the clip 30 therefrom.

In carrying out my invention I aim to provide a clip of the above mentioned character constructed from a single piece of material having a central opening, and a longitudinally extending groove which together 35 with the line of fold between the branch portions intersect said opening at right angles to each other, so that the opening will overlie the edge of the package, whereby 40 a tying cord, should the same be employed would slightly depress the edge of the box and thereby be arranged between the walls of the opening to prevent derangement of the cord upon the package.

45 Other objects will appear as the nature of the invention is better understood from the following description when taken in connection with the accompanying drawing wherein like numerals of reference indicate 50 similar parts in the several views, and in which:—

Figure 1 is a perspective view of the package showing the clips associated therewith. Fig. 2 is a view showing the initial position 55 of the clip during its application. Fig. 3 is an edge view of the clip. Fig. 4 is a bottom

plan view. Fig. 5 is a top plan view. Fig. 6 is a transverse sectional view.

As hereinabove stated the clip forming the subject matter of my invention, is especially designed for use in connection with shipping boxes or the like, and as herein shown A indicates preferably a corrugated cardboard box closed by means of the sealing flaps B, the clips being intended to be arranged in the manner illustrated in Fig. 1.

Each of the clips consists of a single piece of material 5, preferably metal of suitable dimensions and provided with a central opening 6. The material is formed with a longitudinally extending groove 7 and bent along the fold line 8 to provide relatively movable branch portions 9 and 10 respectively, the said groove 7 and fold line 8 intersecting the opening 6 at right angles to each other, for the purpose to be hereinafter described. At the opposite sides of the groove 7 each branch is stamped to provide substantially V-shaped spurs 11, the latter on the branch 9 being arranged at right angles to the spurs on the branch 10. By reason of this arrangement outward pressure upon the top or side walls of the package will not result in the spurs slipping or cutting the package, and becoming casually separated therefrom. Any number of clips may be used with a single package, this depending of course upon the size and shape of the latter, but however I have shown in this specific instance a pair of clips for sealing the closure flaps B.

It will be noted that the branch portions 9 and 10 are normally disposed at an obtuse angle with relation to each other, so that upon the initial application of the clips to the package the spurs 11 on the branch portion 9 are forced to penetrate the sealing flaps B adjacent the meeting edges of the latter, and the portion 10 subsequently bent outwardly and downwardly until the prongs thereon take an effective anchorage in the adjacent side wall of the package. It has been found in practice that when the clip is thus applied the rigidity of both the sealing flap B and the walls of the package is materially increased, and consequently affords considerable protection to the contents of the package. By reason of the fact that the fold line 8 intersects the central opening 6 it will be manifest that in operative position upon the package said opening overlies the edge of the package, so that

when a tying cord is employed to further bind the package, the cord being extended in the groove 7 intersects the opening 6 and when drawn taut will slightly depress the edge of the package, and be positioned between the opposite walls of the opening. The cord in addition to holding the clips effectively in applied position is by reason of its arrangement between the walls of the opening held from being deranged upon the package. The corners of the clip proper as well as the spurs 11 are rounded with a view of eliminating injury to the fingers of the user of the device while applying or removing the same upon the package.

It is believed that from the foregoing description the nature and advantages of the invention will be thoroughly understood without requiring a more extended explanation and therefore the same has been omitted. However I desire to have it under-

stood that various changes in the form, size and minor details of construction may be resorted to when desired as may fall within the scope of the appended claim, without departing from the spirit of the invention.

What is claimed is:—

As a new article of manufacture, a package securing clip constructed from a single piece of material bent to provide relatively 30 movable branches disposed substantially at an obtuse angle with relation to each other, whereby said portions are adapted to be singly moved into engagement with its respective wall of the package, and securing 35 spurs carried by each of said branches.

In testimony whereof I affix my signature in presence of two witnesses.

CHARLES C. GEBHARDT.
